ABSTRACT OF THE DISCLOSURE

A microwave harmonic generator for producing an output at a frequency nf_n ($n=3, 4, 5 \dots$) harmonically related to an input signal at frequency f_0 . The device comprises a rectangular waveguide capable of supporting the input signal in the lowest order transverse mode and terminating in a second waveguide beyond cutoff. A pair of channels extending oppositely from the top and bottom of the waveguide to a depth of one-quarter guide wavelength at $(n-1)f_0$ define a waveguide pseudocavity region resonant at $(n-1)f_0$. Interaction of the input signal with a varactor diode gives rise to energy within the pseudocavity region at harmonically related frequencies; this energy predominantly is at $(n-1)f_0$. Parametric interaction occurs between the confined energy (at $(n-1)f_0$) and the signal (at f_0) to produce an output at nf_0 which may be extracted via the second waveguide. A second pair of grooves oppositely extending from the top and bottom of the waveguide function as a trap to prevent energy at the output frequency from propagating back down the input waveguide.

BACKGROUND OF THE INVENTION

Field of the invention

This invention relates to a microwave harmonic generator and more particularly to a varactor type harmonic generator utilizing a rectangular waveguide having a pseudocavity region therein which is resonant at a harmonic of the input frequency and terminating in an output waveguide whose cutoff frequency lies above the resonant frequency of the pseudocavity region.

Background of the invention

As increasing effort is made to exploit higher and higher microwave frequencies for radar and other purposes, the need for providing RF sources at these extremely high frequencies becomes more important. Present RF sources, such as klystron oscillators, are limited in their very high frequency capabilities and are relatively inefficient at frequencies above about 15 GHz. Above these frequencies, new devices such as Gunn effect oscillators are useful, but these have not yet been developed into operational units except at very low power levels. A more desirable way to provide RF frequencies above 15 GHz. is to employ klystron or other oscillator at a frequency within its efficient operating range and to multiply the frequency of the oscillator output using a harmonic generator.

In the past, a number of harmonic generators have been suggested. For example, the microwave varactor tripler described by C. B. Swan in the Digest of Technical Papers, 1965 International Solid State Circuits Conference (ISSCC), pp. 106-107, utilizes a coaxial matching transformer to introduce an input signal to a varactor diode. The varactor diode is disposed within an output waveguide which is tuned to the third harmonic of the input frequency and which also contains a transverse stub resonant at the second harmonic. A requirement of the

2

Swan device is that the varactor package be resonant at the second harmonic. While this device provides third harmonic output, the requirement that the varactor package be resonant at one of the harmonic frequencies inherently limits the flexibility of the device. When operated at extremely high frequencies, this places severe restrictions on the varactor package dimensions. (The described Swan device converted an input signal at 4 GHz. to an output at 12 GHz.)

Another approach to harmonic generation which is not limited by the inherent characteristics of the varactor package is described by M. E. Hines and J. deKonig on pp. 22 and 23 of the 1967 ISSCC Digest of Technical Papers. This harmonic generator employs a snap varactor in which the capacitance is approximately constant over the useful range of reverse bias. The device uses a cavity resonant at the fundamental frequency. A radial-line coupling gap couples the fundamental cavity to a second radial cavity resonant at the desired harmonic. A snap diode is situated within the second cavity. Coupling to an output coaxial line occurs via holes between the harmonic cavity and the coaxial output line. Tenth harmonic output was reported for the Hines and DeKonig device to derive a 16 GHz. output signal using a 1.6 GHz. input. While a radial configuration is useful at these frequencies, it is very difficult to construct such a radial device at much higher frequencies.

The present invention provides a harmonic generator of simple mechanical design which is capable of operating with input signals above 50 GHz. The inventive harmonic generator is of rectangular configuration, thereby simplifying its construction, and while utilizing a varactor diode, its proper operation does not depend on the resonant frequency of the diode package.

SUMMARY OF THE INVENTION

The inventive harmonic generator comprises a rectangular waveguide having a width sufficient to allow propagation of the input signal in the lowest order transverse mode. The waveguide terminates in a second waveguide, the cutoff frequency of which preferably lies between output frequency nf_0 (where $n=3, 4, 5 \dots$) and $(n-1)f_0$. A pair of channels extending oppositely from the top and bottom of the input waveguide, and having a depth of one-quarter guide wavelength at frequency $(n-1)f_0$, define a pseudocavity region within the input waveguide, which region is resonant at the $(n-1)^{th}$ harmonic of the input frequency f_0 . A varactor diode is disposed within this pseudocavity region. The input signal, when impressed across the back-biased varactor diode, gives rise to energy at harmonically related frequencies. This results because of the nonlinear relationship of current to voltage exhibited by such diodes. Because the diode is disposed within a resonant cavity, the interaction energy is concentrated at the resonant frequency $(n-1)f_0$ and is constrained to within the pseudocavity region. Parametric interaction occurs between the constrained energy (at $(n-1)f_0$) and the input signal (at f_0) to produce an output signal at the sum frequency nf_0 . The output energy, which may be extracted via the second waveguide, is prevented from escaping via the input waveguide by means of a trap comprising a second pair of channels oppositely extending from the top and bottom of the input waveguide to a depth of one-quarter guide wavelength at nf_0 .

The inventive harmonic generator is easy to construct and, in a typical application, may be used as a frequency tripler accepting an input at 60 GHz. and providing an output at 180 GHz.

Thus it is an object of the invention to provide a microwave harmonic generator of simple physical configuration.

Another object of the invention is to provide a harmonic generator having an input waveguide which terminates in a second waveguide beyond cutoff and which contains a pseudocavity region resonant at a harmonic of the input frequency.

It is another object of the invention to provide a simple microwave harmonic generator utilizing a varactor diode to produce parametric interaction between energy constrained at one harmonic frequency $(n-1)f_0$, $n=3, 4, 5 \dots$, within a waveguide pseudocavity region with input energy at the fundamental frequency f_0 to produce an output signal at the sum frequency nf_0 .

A further object of this invention is to provide a microwave harmonic generator utilizing quarter wave channels to provide containment of various harmonic signals to within various regions of a waveguide.

Other objects and features of the invention will become apparent from the following description and drawings which are utilized for illustrative purposes only.

BRIEF DESCRIPTION OF THE DRAWINGS

FIG. 1 is an enlarged, perspective view of a preferred embodiment of the inventive microwave harmonic generator.

FIG. 2 is a cross sectional view of the harmonic generator as viewed generally along the line 2—2 of FIG. 1; a possible electric field distribution within the harmonic generator also is illustrated.

FIG. 3 is a cross sectional view of the inventive harmonic generator as viewed generally along the line 3—3 of FIG. 1.

FIG. 4 is a cross sectional view of the inventive harmonic generator as viewed generally along the lines 4—4 of FIG. 1.

FIG. 5 is another cross sectional view of the inventive harmonic generator as viewed generally along the line 5—5 of FIG. 1; a possible electric field distribution within this region of the harmonic generator also is illustrated.

DESCRIPTION OF THE PREFERRED EMBODIMENT

Referring to FIG. 1, there is shown a greatly enlarged perspective view of a preferred embodiment of the inventive microwave harmonic generator 10. For clarity, harmonic generator 10 is illustrated as being of thin walled construction. However, because of the very small dimensions required for operation at high microwave frequencies, the device more easily may be constructed from several solid blocks of metal which are appropriately milled and assembled to form a device having an interior appearance similar to that shown in FIG. 1. In a typical embodiment having an input frequency of about 60 gHz., the overall length of harmonic generator 10 illustrated in FIG. 1 will be less than 0.5 inch.

The inventive microwave harmonic generator accepts an input signal at a fundamental or first harmonic frequency f_0 and provides an output signal at a frequency which is an integral multiple of the fundamental. Thus, the harmonic generator will provide an output at a frequency nf_0 where $n=3, 4, 5 \dots$. For ease of exposition in portions of the following description, the illustrative embodiment of FIG. 1 will be described in terms of its use as a frequency tripler, providing a third harmonic ($n=3$) output. Throughout, mention will be made of how the various component parameters may be altered to allow generation of any other desired harmonic.

The input signal at fundamental frequency f_0 is introduced into harmonic generator 10 via port 12 at one end of rectangular waveguide section 14. The other end of rectangular waveguide section 14 terminates in shorting plane or wall 16. A second waveguide 40, having a width a' and a height b' also extends from wall 16 and terminates in port 42. In a preferred embodiment, waveguide 40 has a cutoff frequency which lies between the desired

output frequency nf_0 and the frequency $(n-1)f_0$ of the next lower harmonic. Thus, if harmonic generator 10 were to be used to triple an input signal of frequency $f_0=60$ gHz., the third harmonic output at $3f_0=180$ gHz. may be extracted through waveguide 40. In this preferred embodiment, the cutoff frequency of waveguide 40 preferably is about 150 gHz., midway between the second harmonic frequency ($2f_0=120$ gHz.) and the output frequency.

In a preferred embodiment, the interior width a (see FIG. 3) of waveguide 14 is selected to be one-half of the free space wavelength at the fundamental frequency f_0 . Waveguide section 14 has a height b , measured between waveguide top 17 and bottom 18 (see FIG. 2), which preferably is less than width a . With these dimensions, it is possible for the input signal at frequency f_0 to propagate in waveguide section 14 in the lowest order transverse (TE_{10}) mode.

As illustrated most clearly in FIG. 2, a first pair of channels 22 and 22a extend oppositely from top 17 and bottom 18 of waveguide section 14. In a preferred embodiment, channels 22 and 22a have a depth d (see FIG. 4) which is one-quarter of the guide wavelength at the frequency $(n-1)f_0$, where the desired output is at the nth harmonic. (The function of channels 22 and 22a is somewhat similar to the U-shaped waveguide channels described in the copending application to J. N. Lind et al., Ser. No. 617,231, filed Feb. 20, 1967, entitled, "Broadband Microwave Parametric Amplifier," and assigned to North American Aviation, Inc., assignee of the present application.) Thus, in the frequency tripler example, the preferred depth d of channels 22 and 22a is one-quarter of the guide wavelength corresponding to $2f_0$.

Side channels 24 and 24a (see FIG. 1) are provided to achieve desired propagating modes for the harmonic energy present within regions of harmonic generator 10. In a preferred embodiment, channels 24 and 24a have a depth c (see FIG. 5) equal to one-quarter of the width of waveguide section 14 (i.e., $c=a/4$). That is, depth c corresponds approximately to one-eighth of the free-space wavelength of a signal at f_0 . Channels 24 and 24a, which may extend beyond wall 16, further function to ensure suppression of spurious modes within the harmonic generator.

Channels 26 and 26a function as a trap to prevent output energy at the nth harmonic from propagating down rectangular waveguide section 14 toward port 12. In a preferred embodiment, the depth f (see FIG. 3) of channels 26 and 26a is equal to one-quarter of the guide wavelength at output frequency nf_0 . Parameters for selection of the distance g between channels 26 and 26a and diode 30 (see FIG. 2) are described hereinbelow.

A nonlinear reactance such as varactor diode 30 in a preferred embodiment is mounted within pseudocavity region 20 at a location to be described in detail hereinbelow. Diode 30 may, for example, be of the type described in the copending application to D. B. Anderson et al., Ser. No. 361,069, entitled, "High Frequency Diode," and assigned to North American Aviation, Inc., assignee of the present application. Alternately, other varactor diodes may be employed. Diode 30 may be provided with a cone-shaped contact 32, and electrical connections 34 and 36, by means of which an appropriate backward bias voltage may be applied to varactor 30.

In operation, an input signal at fundamental frequency f_0 is introduced into harmonic generator 10 via input port 12. This input signal, harmonics of which are to be generated, will be present throughout waveguide section 14. In a preferred embodiment, an impedance matching network (not shown in the figures) of a type well known to those skilled in the art may be used to insure that a minimum amount of energy at f_0 is reflected back out of port 12 by harmonic generator 10. If the input signal at frequency f_0 is introduced in the lowest order

transverse mode (e.g., the TE_{10} mode) then the signal will not be propagated beyond wall 16, since f_o is well below the cutoff frequency of output waveguide section 40.

Within harmonic generator 10, when the input signal is impressed across back-biased varactor diode 30, energy at various harmonics of f_o will be produced as a result of the nonlinear relation of current to voltage in diode 30. Thus energy will be present in rectangular waveguide section 14 at (among others) the $(n-1)^{th}$ harmonic (where output is desired at the nth harmonic). Since in a preferred embodiment channels 22 and 22a each have a depth of one-quarter guide wavelength at frequency $(n-1)f_o$, the electric field 50 induced in these channels at this frequency will be a maximum in the planes of the top 17 and bottom 18 of rectangular waveguide 14. Since this energy in effect is being generated at varactor diode 30, it will start to propagate back along waveguide section 14. However, when this $(n-1)^{th}$ harmonic signal reaches the area between grooves 22 and 22a, it will see an extremely high impedance due to the electric field maxima at this location. As a result the $(n-1)^{th}$ harmonic signal will not propagate further along waveguide 14 toward input port 12. Further, since the cutoff frequency of output waveguide 40 is higher than $(n-1)f_o$, this $(n-1)^{th}$ harmonic will not be propagated out of harmonic generator 10 via waveguide 40. Thus energy at frequency $(n-1)f_o$ will be constrained entirely to within pseudocavity region 20.

If the length 1 (see FIG. 2) of pseudocavity region 20 is made to be an integral number of one-half guide wavelengths plus one-quarter guide wavelength at the frequency $(n-1)f_o$, then pseudocavity region 20 will function as a resonant cavity at this $(n-1)^{th}$ harmonic. In a preferred embodiment, the length 1 is selected to be three-quarters guide wavelength at the frequency of $(n-1)f_o$. Thus, when used as a frequency tripler, the electric field distribution within pseudocavity region 20 at the second harmonic may have the appearance illustrated by solid arrows 50 in FIG. 2. In a direction perpendicular to the longitudinal axis of waveguide section 14, the electric field at the frequency $(n-1)f_o = 2f_o$ may, in a preferred embodiment, have the distribution shown by arrows 52 in FIG. 5. Note that this distribution (which corresponds to a TE_{230} mode) results since the width a was selected to be one-half free space wavelength, and the depth c selected to be one-eighth free space wavelength at the fundamental frequency f_o . Thus the dimension a will be slightly longer than one free space wavelength, and the dimension c will be slightly longer than one-quarter free space wavelength, at the second harmonic $2f_o$.

With the preferred configuration described, pseudocavity region 20 of harmonic generator 10 will exhibit a high Q at the frequency $(n-1)f_o$. Thus when a signal at input frequency f_o is introduced into waveguide section 14, the harmonic energy generated by interaction with nonlinear reactance 30 will result in a preponderance of energy in the $(n-1)^{th}$ harmonic. For example, in the exemplary frequency tripler embodiment, the energy will be concentrated in the second harmonic, and may have the standing wave pattern illustrated in FIGS. 2 and 5.

To produce an output at frequency $n f_o$, harmonic generator 10 functions in a manner resembling a parametric up-converter. (A good theoretical exposition of parametric interaction is contained in the text entitled "Coupled Modes and Parametric Electronics," by William H. Louisell, published in 1960 by John Wiley and Sons, N.Y.) The signal, at fundamental frequency f_o , is introduced into waveguide section 14 via port 12 and the "pump," at a frequency $(n-1)f_o$, is induced into pseudocavity region 20 as a result of the nonlinear current-voltage characteristics of diode 30, as described hereinabove. (Note that when used as a frequency tripler, the device in effect is operating in the degenerate parametric mode, with the "pump" frequency $2f_o$ equal to twice the signal

frequency f_o .) In contrast to usual parametric device operation, energy is being fed to harmonic generator 10 only at the signal frequency, and not also at the pump frequency. Rather, the "pump" energy is derived completely within harmonic generator 10 from the signal. In a preferred embodiment, varactor diode 30 is situated at the "pump" voltage maximum midway between channels 24 and 24a (see FIG. 5) and one-half guide wavelength (at $(n-1)f_o$) from wall 16 (see FIG. 2). Parametric interaction occurs between the signal at f_o and the "pump" at $(n-1)f_o$, and results in production of energy at the idler frequency $n f_o$, the sum of the pump and signal frequencies. This energy, which will be present in pseudocavity region 20, is at just the desired n^{th} harmonic.

The energy generated at the nth harmonic may be extracted from harmonic generator 10 via waveguide 40, which, as noted above, has a cutoff frequency below $n f_o$. In a preferred embodiment, an impedance matching network (of a type well known to those skilled in the art), not shown in the figures, may be provided between output port 42 and the load which is to utilize the harmonic generator output signal. This impedance matching network will function to match the impedance of the load to that of harmonic generator 10 and to minimize the amount of energy (at $n f_o$) reflected back into the generator.

Channels 26 and 26a serve as a filter or trap to prevent energy at the output frequency $n f_o$ from propagating out of harmonic generator 10 via waveguide section 14. To perform this function, in a preferred embodiment channels 26 and 26a have a depth (see FIG. 3) of one-quarter guide wavelength at $n f_o$, and are located at a distance g (see FIG. 2) which is an integral number of one-half guide wavelengths (at $n f_o$) from varactor diode 30. Moreover, channels 26 and 26a preferably should extend from waveguide section 14 at a location between channels 22 and 22a and input port 12, as illustrated in FIGS. 1 and 2.

In the exemplary harmonic tripler, channels 26 and 26a may be placed one wavelength (i.e. two half wavelengths) at $3f_o$ from varactor diode 30; in this case, the electric field distribution at the output frequency may have the appearance illustrated by dashed arrows 56 in FIG. 2. Note that the third harmonic (output) energy will see a very high impedance in the area of channels 26 and 26a, caused by the voltage maxima present in channels 26 and 26a in the plane of waveguide top 17 and bottom 18. This will effectively prevent energy at the output frequency from propagating further down waveguide section 14 toward input port 12. Although not shown in FIG. 5, the tripler output energy at $3f_o$ will extend into side channels 24 and 24a, and, in a preferred embodiment may be present in harmonic generator 10 in the TE_{330} mode. Thus the harmonic generator will produce an output at frequency $n f_o$ which will propagate down waveguide 40 and be available at output port 42.

While the inventive harmonic generator has been described in terms of an embodiment having opposing pairs of channels 22 and 22a this is not required. Rather a single channel (i.e., either 22 or 22a) extending from either top 17 or bottom 18 of waveguide section 14 may suffice to define pseudocavity region 20. However, when only one such channel is used, energy at the $(n-1)^{th}$ harmonic may not be constrained within region 20 to the same degree as when opposing channels are used. This will result in somewhat lower harmonic generator efficiency. In an alternate configuration, an additional channel or pair of channels may be added between channels 22 and 22a and the output harmonic trap (channels 26 and 26a) to form a second pseudocavity region. This will provide additional containment of the energy at $(n-1)f_o$, and may improve the conversion efficiency of harmonic generator 10.

Similarly, it may be possible to dispense with either channel 26 or 26a and still achieve sufficient trapping of the output energy with the remaining single channel filter. On the other hand, an additional pair of channels,

one-quarter guide wavelength deep at the output frequency, may be added (between channels 26 and 26a and input port 12) to provide additional attenuation of output energy propagating toward port 12.

We claim:

1. A harmonic generator comprising:
a rectangular waveguide capable of supporting energy at a fundamental frequency and terminating in a shorting plane,
a first pair of channels oppositely extending from the walls of said waveguide, said channels having a depth of one-quarter guide wavelength at a first frequency harmonically related to said fundamental frequency, and
a varactor diode disposed within said waveguide between said channels and said shorting plane.

15
2. A harmonic generator as defined in claim 1 further comprising a second pair of channels oppositely extending from the walls of said waveguide, said second pair of channels having a depth of one-quarter guide wavelength at a second frequency, said second frequency being harmonically related to said fundamental frequency and higher than said first frequency, said second pair of channels extending the entire width of said waveguide and being situated between said first pair of channels and the 20 nonshorted end of said waveguide.

3. A harmonic generator as defined in claim 2 further comprising a second waveguide extending from said shorting plane and having a cutoff frequency between said first and second frequencies.

30
4. A harmonic generator as defined in claim 3 wherein said first pair of channels extend the entire width of said waveguide, wherein said waveguide has a width equal to one-half free-space wavelength of said fundamental frequency, and wherein said first pair of channels are 35 situated an odd number of one-quarter guide wavelengths at said first frequency from said shorting plane.

5. A harmonic generator as defined in claim 4 further including means for controlling the mode in which energy is present in regions of said waveguide, said means comprising first and second pairs of side channels extending from said waveguide to a depth of approximately one-eighth free-space wavelength at said fundamental frequency, said pairs of channels being parallel to the longitudinal axis of said waveguide.

45
6. A harmonic generator for converting an input signal at a fundamental frequency f_0 to an output at a harmonically related frequency nf_0 (where $n=3, 4, 5 \dots$) comprising, in combination:

50
a waveguide capable of supporting signal at frequency f_0 ,
means comprising at least one channel extending from the wall of said waveguide to a depth of essentially one-quarter guide wavelength at a frequency $(n-1)f_0$ for providing a resonant region at frequency 55 $(n-1)f_0$ within said waveguide, and
nonlinear reactance means, comprising a varactor diode disposed within said region, for producing energy at $(n-1)f_0$ and to provide an output at nf_0 .

60
7. A harmonic generator as defined in claim 6 further including trap means, comprising at least one channel extending from the wall of said waveguide to a depth of essentially one-quarter guide wavelength at frequency nf_0 , for preventing energy at frequency nf_0 from propagating down said waveguide beyond said trap means.

65
8. A harmonic generator as defined in claim 7 wherein

said waveguide terminates in a second waveguide, said second waveguide having a cutoff frequency between $(n-1)f_0$ and nf_0 .

9. A microwave harmonic generator for converting an input signal at a frequency f_0 to an output signal at a frequency nf_0 (where n is an integer greater than 2), said generator comprising, in combination:

a first waveguide capable of supporting a signal at frequency f_0 in the lowest order transverse mode and terminating in a shorting plane,
a second waveguide having a cutoff frequency between nf_0 and $(n-1)f_0$ said second waveguide extending from said shorting plane,
means comprising at least one channel extending from said waveguide to a depth of one-quarter guide wavelength at a frequency $(n-1)f_0$, for providing a pseudocavity region within said first waveguide, said region being resonant at $(n-1)f_0$,
a varactor diode disposed within said pseudocavity region, and
trap means, comprising a second pair of channels oppositely extending from said first waveguide to a depth of one-quarter guide wavelength at a frequency of nf_0 , for preventing energy at the output frequency from propagating down said first waveguide beyond said trap means.

10. A microwave frequency tripler comprising, in combination:

a first waveguide capable of supporting a signal at a fundamental frequency in the lowest order transverse mode and terminating in a shorting plane,
a second waveguide having a cutoff frequency between the second and third harmonics of said fundamental, said second waveguide extending from said shorting plane,
a first pair of channels extending from said first waveguide to a depth of one-quarter guide wavelength at said second harmonic, said channels extending the entire width of said waveguide and being located three-quarters of a guide wavelength at said second harmonic from said shorting plane,
a varactor diode disposed within said first waveguide at a location equidistant from the sides of said waveguide and one-quarter guide wavelength at said second harmonic from said shorting plane, and
a second pair of channels oppositely extending from said first waveguide to a depth of one-quarter guide wavelength at said third harmonic, said channels extending the entire width of said waveguide and being located one guide wavelength at said third harmonic from said diode.
